PAUL J. ST. JEAN, OF THOMPSONVILLE, CONNECTICUT, ASSIGNOR TO BIGELOW-SAN-FORD CARPET CO., INC., OF THOMPSONVILLE, CONNECTICUT, A CORPORATION OF MASSACHUSETTS

FILLING REPLENISHING LOOM

Application filed September 19, 1930. Serial No. 482,995.

This invention relates to filling replenishing looms wherein the filling is changed from time to time either by the substitution of a fresh shuttle for that which has become depleted or by a change of the filling carrier in the shuttle for a fresh filling carrier.

In filling replenishing looms it is desirable that the outgoing and incoming filling end be parted at the replenishing side of the loom and that in case the filling fails at this point the loom be stopped.

Heretofore it has been common to provide filling or weft fork mechanisms to stop the loom in case of filling failure, and also to cut or part the incoming and outgoing filling ends. In looms for weft pile fabrics, however, where the ends of the pile wires extend beyond the edge or selvage of the cloth and are accumulated in this position for a number of picks, the problem of effecting the foregoing desirable results becomes complicated, and one of the objects of the present invention is to provide means for effecting loom stoppage through the filling fork when filling fails to be laid in the shed and to cut or part the filling ends at the side of the loom adjacent the replenishing mechanism.

More specifically stated, the weft fork actuating slide and the cutting or parting mechanism are each actuated by a novel train of devices disposed at the filling replenishing side of the loom and adapted to be operated through or by the lay movements.

The invention and novel features thereof will best be made clear from the following description and the accompanying drawings of one good form thereof.

In the drawings:

Fig. 1 is a perspective view of parts of a shuttle replenishing loom provided with the features of the present invention;

Fig. 2 is a vertical sectional view through the lay of the loom of Fig. 1, looking towards the filling fork mechanism;

Fig. 3 is a top plan view of parts shown in Fig. 2;

Fig. 4 is a view similar to Fig. 2 but shows the relation of parts when the shuttle is at the far side of the loom; and

Fig. 5 is a sectional view taken on the line 5—5 of Fig. 4.

The features of the present invention have been illustrated in connection with a pile fabric loom provided with shuttle transfer mechanism similar to that more fully shown and described in the Edwin W. Stone application, Serial No. 481,841 filed Sept. 15, 1930.

The loom shown has the breast beam or supporting structure 1 in front of which is disposed the usual take-up roll 2 about which the woven fabric F is advanced during the weaving operation, in a well-known manner.

The loom is also provided with the usual lay 3 supported by the lay swords 4 for movement towards and from the front of the loom and the lay is provided with the reed 5 which is supported at its upper end by the reed cap 6, the opposite ends of this reed cap being secured to the extensions 7 provided at the upper ends of the lay swords.

At the left-hand side of the loom illustrated in Fig. 1 is provided the shuttle replenishing mechanism comprising the shuttle magazine 8 which is adjustably supported by the bracket 9 secured to the loom frame.

The shuttle box at the rear of the shuttle magazine 8 is shown as having a movable front wall 10 adapted to be carried upwardly by the supporting arms 11 in a manner fully set forth in the application above mentioned, to permit the exhausted shuttle to be discharged from the lay and a full shuttle supplied thereto from the shuttle magazine 8. The full shuttle is carried from the magazine 8 to the shuttle box by the transpeller 12.

The loom illustrated is adapted to weave a pile fabric and is shown as provided with pile wires 13, the forward ends of which are shown in Fig. 3 as extending some distance from the selvage at the left-hand side of the fabric F.

The features so far described form no essential part of the present invention but have been illustrated and briefly set forth to make clear the construction and location of the filling fork and shear mechanism to be described, and the novel mechanism of the present invention for imparting a de-

tecting movement to the slide operating lever and for operating the shear blade. The filling fork mechanism illustrated comprises a trough-shaped stand 14 which is rigidly secured to the breast beam or main frame of the loom in position to clear the ends 13 of the pile wires, as shown, and in this stand is slidably mounted the filling fork slide 15. The slide preferably has the U-shaped construction best shown in Fig. 3 and is provided at its rear end with the transversely-extending pin 16 on which is pivotally mounted the filling fork 17 which may have the U-shaped forwardly extending end portion 18 and the downwardly extending tines 19 of well-known construction.

The lay 3 is shown as having the usual transversely extending clearance slot 20 adapted to receive the lower ends of the tines 19. The filling fork is supported by the filling fork slide 15 so that the tines 19 will cooperate with the grid 21 to detect the presence or absence of filling laid by the shuttle when the shuttle is in the left-hand box, viewing Fig. 1.

The construction of the filling fork mechanism illustrated is such that if filling is present when the lay beats up, the filling or weft thread *a* will lie between the tines 19 of the filling fork and the grid 21 and will cause the fork to tilt in a well-known manner so that its end 18 will clear the vibrator or slide operating lever, to be described; whereas, if the filling or weft is absent, as in Fig. 4, when the lay moves forwardly on a detecting beat, the fork will not be tilted, and consequently it will be engaged by the vibrator or slide operating lever, with the result that the slide 15 will be moved forwardly to stop the loom.

In the present construction, the filling fork slide 15 is continuously urged rearwardly towards the stop 22 by the coiled spring 23 surrounding the guide rod 24 which is secured to the filling fork slide and extends forwardly through an opening in the fixed post 25 to slide therein.

In the construction illustrated, the forward movement of the slide 15 and rod 24 serves to rock the switch operating lever 26 adapted to actuate switch mechanism within the switch box 27 and thereby effect loom stoppage.

While, as above stated, filling forks and filling parters have been frequently employed heretofore, the vibrator or slide operating lever for moving the filling fork slide forwardly when filling is absent on a detecting beat, has been commonly actuated from a cam 30 on the bottom or cam shaft, and the filling parter has been operated by separate and independent means from that employed to actuate the vibrator or slide operating lever.

The present invention departs from these prior forms of operating means by employ-

ing the same actuator for operating the slide operating lever and filling parter, and by employing the lay movement to operate this actuator.

In accordance with the present invention, the means for moving the filling fork slide forwardly when an absence of filling is detected comprises a slide operating lever 28, the lower end of which is pivotally supported by the pin 29 carried by the bracket or housing 30 secured to the loom frame, and the lever 28 is continuously urged towards the dotted line position of Fig. 2 by the coiled spring 31. The lever 28 is shown as having a head or enlargement at its upper end and this head is provided with a shoulder 32 adapted to engage the looped portion 18 of the filling fork when the latter remains in the lowered position of Fig. 4, upon a detecting beat of the lever 28.

The movement of the lay is utilized in accordance with the present invention to actuate the lever 28 and this is accomplished by providing this lever with a laterally extending arm 33 which may also be mounted on the pin 29 and the arm is rigidly secured to the lever 28 in the desired position of adjustment by forming an elongated slot 34 in the arm 33 to receive the clamping bolt 35. The arm 33 is provided at its outer end with a roller 36 and is adapted to be actuated by a cam 37 rigidly secured to the shaft 38. This shaft is journaled in the side walls 39 of the housing 30 for rocking movement. The arrangement is such that so long as the cam 37 occupies the position in which it is shown in Fig. 4 the slide operating lever 28 will remain in its rearward or inactive position, but movement of the cam 37 to the position in which it is shown in Fig. 2 will act upon the roller 36 to force the lever 28 forwardly to the position in which it is shown in full lines in Fig. 2.

The desired rocking movement is imparted to the shaft 38 by rigidly securing to this shaft the actuating cam 39 having the V-shaped nose 40 and notches 41 disposed at the opposite sides of the nose 40.

The actuating cam 39 is adapted to be engaged each time the lay beats up by a plunger 42 carried by the lay. This plunger in the construction shown is pivotally secured at 43 to the bracket 44 on the lay, and the plunger 42 is normally held in the horizontal position in which it is shown in Fig. 1 by springs 45 mounted on the rod 46 supported by the ears 47. The rod 46 extends through a hole 48 in the plunger 42. The arrangement is such that the plunger 42 may be rocked in either an upward or a downward direction from its normally horizontal position but as soon as the plunger is released it will be returned to its horizontal position by the expanding action of the springs 45.

As a result of the construction just de-

scribed, the plunger 42 will be depressed by the nose 40 into the lower notch 41 during one forward movement of the lay to thereby rock the parts into the position in which they are shown in Fig. 2, and upon the next forward movement of the lay the nose 40 will deflect the plunger 42 upwardly to engage the upper notch 41, and this will serve to rock the parts to the position in which they are shown in

10 Fig. 4. As the result of this construction the slide operating lever remains in its rearward inactive position during one beat-up movement of the lay but is moved forwardly upon the next beat-up movement of the lay 15 and remains in this forward position until the operating cam 37 is again rocked in a downward direction so that the lever 28 may return to its rearward position under the action of the spring 31.

20 It will be seen from the foregoing that the plunger 42 operates the cams 37 and 39 so that they will impart a detecting beat to the lever 28 only upon every other forward movement of the lay, and as a result the filling fork 25 slide will be forced forwardly only when the shuttle is in the left-hand box, viewing Fig. 1, and the filling fails to tilt the filling fork sufficiently to clear the shoulder 32 of the slide operating lever.

30 It is apparent that when filling replenishment is effected, a trailing end of filling will be formed extending from the cloth selvage. In the construction shown, two of these trailing ends are formed, one by the ejected exhausted shuttle and the other by the new shuttle. It is desirable to part these trailing ends so that they will not be carried into the shed, and shearing means to this end may comprise a fixed shear blade 49 rigidly secured 35 to the stand 14 and a movable shear blade 50 supported by the pivotal pin 51, and the movable blade 50 is preferably yieldingly held against the fixed blade by the coiled spring 52 provided upon the pin 51 between 40 the movable blade and nuts 53.

45 The movable shear blade 50 is actuated in accordance with the present invention from the rocking shaft 38, and to this end the shaft 38 is provided with an actuating arm 54 which 50 is operatively connected to the rear end portion of the blade 50 by the connecting link 55. The arrangement is such that one beat-up movement of the lay will rock the shaft 38 in a direction to open the shear blade 50 and the next beat-up movement of the lay will close this shear blade to clip the trailing filling, provided the same has been advanced 55 frontwardly by the fabric F between the blades 49 and 50.

60 The coiled spring 52 serves to create sufficient friction between the cooperating blades 49 and 50 to cause the blade 50 to remain in either its open or closed position until it is 65 positively shifted from such position by the

plunger 42 upon the next forward movement of the lay.

70 It will be seen from the foregoing that through the mechanism of the present invention the forward movement of the lay is utilized to operate both the slide operating lever and filling shearing mechanism, and that the mechanism for operating these elements is simple in construction and reliable in operation.

75 What is claimed is:

1. In a loom, the combination of the lay, a filling fork, means for supporting the fork in position to detect the presence or absence of filling, a lever adapted to engage and shift the fork when filling is absent on a detecting beat, a filling end parter, and means operable by the lay movement for actuating the parter and for imparting detecting movement to said lever. 80

85 2. In a loom, the combination of the lay, a filling end parter, a filling fork slide, a filling fork supported by the slide in position to detect the presence or absence of filling, a slide operating lever adapted to engage the fork and shift the slide when filling is absent on a detecting beat, and means operable by movement of the lay to actuate said parter and adapted to impart a detecting movement to said lever only upon every other forward beat of the lay. 90

95 3. In a loom, the combination of the lay, a filling fork slide, a filling fork supported by the slide in position to detect the presence or absence of filling, a slide operating lever adapted to engage the fork and shift the slide when filling is absent on a detecting beat, a pivotally mounted actuator for shifting said lever, means upon the lay and operable by the lay movement to shift the actuator, shear blades mounted adjacent said slide, and means for operating one of the shear blades from said actuators. 100

105 4. In a loom, the combination of the lay, a filling fork slide, a filling fork supported by the slide in position to detect the presence or absence of filling, a slide operating lever adapted to engage the fork and shift the slide when filling is absent on a detecting beat, a thread parter and means upon the lay for imparting detecting movement to said lever and thread parting movement to the thread parter. 110

115 5. In a loom, the combination of the lay, a filling fork, means for supporting the fork in position to detect the presence or absence of filling, a lever mounted for oscillating movement and adapted to engage and shift said fork when filling is absent on a detecting beat, and means operable by lay movement to impart an oscillating detecting movement to said lever upon every other forward beat of the lay and a non-detecting movement on intermediate beats. 120

125 6. In a loom, the combination of the lay, a 130

- filling fork, means for supporting the fork independently of the lay in position to detect the presence or absence of filling, a lever pivotally mounted for oscillating movement and adapted to engage and shift said fork when filling is absent on a detecting beat, and means upon the lay for imparting an oscillating movement to said lever in both its detecting and non-detecting movements.
7. In a loom, the combination of the lay, a filling fork slide mounted upon a fixed portion of the loom, a filling fork supported by the slide in position to detect the presence or absence of filling, means operable by the movement of said slide to effect a change in the operation of the loom, a slide operating lever adapted to engage the fork and shift the slide when filling is absent on a detecting beat a thread parter adjacent the filling fork slide, and means carried by the lay for imparting a detecting movement to said lever and cutting movement to the thread parter.
8. In a loom, the combination of the lay, a filling fork slide, a filling fork supported by the slide in position to detect the presence or absence of filling, a slide operating lever adapted to engage the fork and shift the slide when filling is absent on a detecting beat, a cam for shifting said lever in one direction upon one beat-up movement of the lay and in the opposite direction upon the next beat-up movement of the lay, and means upon the lay and operable by the lay movement to actuate the cam.
9. In a loom, the combination of the lay, a filling fork slide, a filling fork supported by the slide in position to detect the presence or absence of filling, a slide operating lever adapted to engage the fork and shift the slide when filling is absent on a detecting beat, a rocking cam for shifting said lever, and means upon the lay and operable to rock the cam in one direction upon one beat of the lay and in the opposite direction upon the next beat of the lay.
10. In a loom, the combination of the lay, shear blades for parting filling extending from the cloth selvage, and means for operating one of said blades to sever the filling including a part carried by the lay and operable to open the blade upon one beat-up movement and to close the blade upon the next beat-up movement.
11. In a loom, the combination of the lay, shear blades for parting filling extending from the cloth selvage, pivotal means for shifting one of said blades, and an actuator carried by the lay to shift said means to one position upon one beat-up movement of the lay and to a second position upon the next beat-up movement of the lay.
12. In a loom, the combination of the lay, shear blades for parting filling extending from the selvage, a pivotally mounted actuator for the shear blade, and means carried by the lay and operable to rock said actuator in one direction upon one beat-up movement to open the blade and in the opposite direction upon the next beat-up movement to close the blade.
13. In a loom, the combination of the lay, a filling fork slide, a filling fork supported by the slide in position to detect the presence or absence of filling, a slide operating lever adapted to engage the fork and shift the slide when filling is absent on a detecting beat, and means for shifting said lever including a pivotally mounted actuator having a projecting nose and a notch at each side of the nose, and a plunger pivotally mounted upon the lay in position to engage said nose as the lay beats up and adapted to be deflected by the nose into engagement with one notch upon one beat-up and the other notch upon the next beat-up.
14. In a loom for weaving pile fabrics, the combination of the lay, a filling fork, means for supporting the filling fork beyond the ends of the pile forming wires in position to detect the presence or absence of filling, a lever adapted to engage and shift the fork when filling is absent on a detecting beat, a filling end parter adjacent the filling fork slide, and means operable by the lay movement for actuating the parter and for imparting detecting movement to said lever.
- In testimony whereof, I have signed my name to this specification.
- PAUL J. ST. JEAN.
